UNITED STATES PATENT OFFICE.

MERTON S. LEONARD, OF BOSTON, MASSACHUSETTS, ASSIGNOR TO B. F. STURTEVANT COMPANY, OF BOSTON, MASSACHUSETTS, A CORPORATION OF MASSACHUSETTS.

CENTRIFUGAL FAN-WHEEL.

1,331,071.

Specification of Letters Patent. Patented Feb. 17, 1920.

Application filed December 31, 1915. Serial No. 69,602.

To all whom it may concern:

Be it known that I, MERTON S. LEONARD, a citizen of the United States, residing at Boston, in the county of Suffolk and State 5 of Massachusetts, have invented certain new and useful Improvements in Centrifugal Fan-Wheels; and I do hereby declare the following to be a full, clear, and exact description of the invention, such as will enable others skilled in the art to which it 10 pertains to make and use the same.

The invention relates to centrifugal fan wheels which take the air in axially and discharge it circumferentially, and which 15 are adapted for acting upon air carrying abrasive material which abrades or wears away the blades with which it comes in contact.

The object of the invention is to provide 20 a novel and improved construction of fan wheel which will so distribute the abrasion caused by the abrasive material that the strength of the wheel will not be seriously affected thereby, and which will enable the 25 wheel to be conveniently and economically repaired. To these ends the invention contemplates providing the wheel with a series of blades which extend inward beyond the inner edges of a series of intermediate 30 blades and which are independent of the wheel supporting devices, and so securing the inwardly extending blades that they may be readily removed and replaced. With this construction, any abrasive material 35 carried by the air entering the intake chamber of the wheel will be picked up and carried along over the faces of the inwardly extending blades before the air reaches the inner edges of the intermediate blades, so 40 that the wear due to the abrasive material is practically confined to the inwardly extending blades. The wearing away of these blades will not materially affect the structural strength of the wheel or of its sup- 45 porting devices, and the wheel may therefore remain in use without repair or danger of accident until the inwardly extending blades are substantially worn away. The worn blades may then be readily and 50 quickly replaced by new blades, which will in turn be worn out and replaced, while the main structure of the wheel remains intact.

The invention will be readily understood

from an inspection of the accompanying drawings and the following detailed description of the fan wheel illustrated therein. 55

In the drawings, Figure 1 is a side elevation of a fan wheel embodying the invention in its preferred form; Fig. 2 is a sectional view on line 2—2, Fig. 1; and Fig. 3 is a 60 detailed sectional view on line 3—3, Fig. 1.

The invention is shown in the drawings as embodied in a high speed centrifugal blast fan adapted to handle or carry abrasive material or material in which abrasive foreign matter is liable to be present. 65

As shown, the wheel comprises the annular side blades 2 between which the blades of the fan are secured, and the central supporting spider having a hub 4 and radial arms 6, to the outer ends of which certain of the fan blades are secured. In the construction shown, every third blade 8 of the fan wheel extends in toward the center of the wheel beyond the inner edges of the intermediate blades 10 to which the arms of its supporting spider are connected, so that the inner portions of the blades 8 project into the intake chamber 12 of the wheel, and will pick up any abrasive material entering 75 the intake chamber with the air before it has passed radially outward far enough to strike the inner portions of the shallower intermediate blades. The abrasive material will therefore be distributed on the in- 80 wardly projecting blades 8, and will abrade and wear away these blades to which the arms of the supporting spider are attached, while the intermediate blades will be practically unaffected. The wearing away of the 85 blades 8 will not seriously weaken the wheel, since sufficient strength to withstand the strains developed during its use is afforded by the unworn intermediate blades, the side plates, and the supporting spider. 95

In order that the blades 8 may be readily removed when worn out, and replaced by new blades, they are provided with side flanges 12 which are secured to the side plates by bolts and nuts 14. Since the intermediate blades 10 form a permanent part of the wheel structure, their side flanges are 100 preferably secured to the plates by rivets 16.

While it is preferred to employ the specific construction and arrangement of parts 105 shown and described, it will be understood

that this construction and arrangement is not essential to the broader features of the invention, and may be varied and modified without departing therefrom.

5 Having explained the nature and object of the invention, and specifically described one form of mechanism in which it may be embodied, what is claimed is:—

10 1. A centrifugal fan wheel comprising a hub, spokes extending therefrom, side plates, air handling blades, means for permanently securing the spokes, plates and blades in proper relation, intermediate material handling blades, extending inwardly beyond 15 said air handling blades for picking up and handling abrasive material, and means for removably securing the material handling blades to the side plates to permit the ready removal and replacement of said blades

without disturbing the connections between 20 the spokes, plates and air handling blades.

2. A centrifugal fan wheel comprising a hub, spokes extending therefrom, a driving blade permanently secured to each spoke, an annular side plate permanently secured to 25 the axial ends of each of said blades, and a plurality of material handling blades for picking upon and handling abrasive material, said blades extending inwardly beyond the driving blades and being located one 30 between adjacent driving blades, and means for removably securing the material handling blades to the side plates to permit the ready removal and replacement of the material handling blades without disturbing 35 the connections of the driving blades with the spokes and with the side plates.

MERTON S. LEONARD.

Corrections in Letters Patent No. 1,331,071.

It is hereby certified that in Letters Patent No. 1,331,071, granted February 17, 1920, upon the application of Merton S. Leonard, of Boston, Massachusetts, for an improvement in "Centrifugal Fan-Wheels," errors appear in the printed specification requiring correction as follows: Page 1, lines 87-88, strike out the words "to which the arms of the supporting spider are attached"; same page, line 89, after the word "blades" insert the words *to which the arms of the supporting spider are attached*; and that the said Letters Patent should be read with these corrections therein that the same may conform to the record of the case in the Patent Office.

Signed and sealed this 30th day of March, A. D., 1920.

[SEAL.]

M. H. COULSTON,

Acting Commissioner of Patents.
